UNITED STATES PATENT OFFICE.

RICHARD S. GIESE, OF PITTSBURGH, PENNSYLVANIA.

DESIGN FOR THE SURFACE ORNAMENTATION OF A SHADE, GLOBE, OR ILLUMINATING-BOWL.

56,866.

Specification for Design.

Patented Jan. 4, 1921.

Application filed April 26, 1920. Serial No. 376,861. Term of patent 7 years.

To all whom it may concern:

Be it known that I, RICHARD S. GIESE, a citizen of the United States, residing at Pittsburgh, in the county of Allegheny and State of Pennsylvania, have invented a new, original, and ornamental Design for the Surface Ornamentation of a Shade, Globe, or Illuminating-Bowl, of which the following is a specification, reference being had to the accompanying drawing, forming part hereof.

The figure is an elevation of a shade, globe, or illuminating bowl for electric or gas lights, showing my new design. The design

relates to the surface ornamentation disclosed in the drawing, and may be applied to any shape of shade, globe or illuminating bowl designed for use for electric or gas lights.

I claim:—

The ornamental design for the surface ornamentation of a shade, globe, or illuminating bowl, substantially as shown.

In testimony, that I claim the foregoing as my own, I have hereto affixed my signature.

RICHARD S. GIESE.
